SETTING MECHANISM

Commodore D. Ryan and Herschel L. Atherton,
Los Angeles, Calif., assignors to National Postal
Meter Company, Inc., Rochester, N. Y., a cor-
poration of Delaware

Application May 21, 1941, Serial No. 394,518

6 Claims. (Cl. 192—8)

This invention relates to mechanisms for setting such devices as postage printing machines, cash registers, and like, in which a dial, lever or segment is movable into a plurality of different positions of rotation representative of different values, and yieldably retained in any one of several different positions by a detent mechanism. The detent mechanism usually comprises a disc or segment rotatable with the setting mechanism and having a notched, arcuate edge which engages with a spring detent, the latter when in full engagement with a notch, yieldably retaining the mechanism in a position representative of a certain value. The spring detent yields in response to the application of a predetermined torque to the notched disc to permit it to rotate into another position in which the detent fully engages another notch, but prevents the device from being stopped in any position other than one in which the detent is in full engagement with a notch.

An object of the present invention is to reduce the torque required to rotate an indexing device having a detent mechanism of the general type referred to, without rendering the detent mechanism any less effective for its intended purpose, namely, to prevent accidental movement of the mechanism out of the desired position.

Another object of the invention is to provide a detent mechanism that is capable of positively locking the indexing device against accidental movement without interfering with its normal movement when actuated by the operator.

It is common in postage meters to provide a setting mechanism employing a plurality of indexing levers each movable through a substantial angle for setting the machine to print different values of postage. It is found that where the resistance to movement of the levers is high, the finger fatigue resulting from repeated operation of the indexing levers over a substantial period of time becomes quite serious. The resistance to motion of the indexing levers may be divided into two main components: (1) that resulting from friction inherent in the value-changing mechanism, and (2), the resistance to movement afforded by the detent mechanism. It is found from actual tests on an existing machine of the old type, that where the total force required to move the indexing lever is 4½ lbs. only 1½ lbs. or one-third of the total is used in overcoming the friction inherent in the setting mechanism, the remaining two-thirds being required to overcome the resistance afforded by the detent mechanism. This additional resistance to motion introduced

by the detent mechanism is objectionable not only because of its relatively large magnitude but because it rises and falls each time a tooth of the segment passes the spring detent. It is not feasible to reduce the force exerted by the detent spring, as to do so would increase the danger of accidental movement of the mechanism.

However, in accordance with the present invention, we have discovered that it is possible to substantially reduce the force required to manually rock the indexing lever without reducing the force exerted by the detent spring, by providing an auxiliary mechanism actuated by initial movement of the indexing lever for carrying the spring detent substantially clear of the toothed segment, only during movement of the indexing mechanism into a new position, the mechanism releasing the spring detent for normal, full, retaining effect on its associated segment when the indexing lever is released by the operator. Furthermore, we are able, with our construction, to positively lock the toothed segment with the detent except during movement of the mechanism into a new position by the operator.

The invention may be fully understood from the following detailed description with reference to the drawing of a particular embodiment thereof, in which:

Fig. 1 is a face view of a detent mechanism in accordance with the present invention;

Fig. 2 is a view similar to Fig. 1, but showing the parts in a different position of operation;

Fig. 3 is a sectional view, taken in the plane III—III of Fig. 1;

Fig. 4 is a sectional view, taken along the line IV—IV of Fig. 1; and

Fig. 5 is a fragmentary view of a portion of the mechanism shown in Fig. 1, but showing an alternative construction.

There is shown in the drawing a single indexing lever 1 and associated mechanism for rotating a shaft 2, which shaft drives any suitable settable mechanism (not shown). The particular device disclosed is for setting a printing wheel

in a postage printing machine, and the shaft 2 is rotatable through an arc of approximately 90° to vary the value printed from "0" to "9". The shaft 2 has rigidly connected thereto, as through a hub 3, a dial 4 on which the different numerals 5 are imprinted. In a complete machine a pointer, a window or other indexing device cooperates with the numerals 5 to visibly indicate the setting of the shaft 2 at all times.

To insure that the shaft 2 and dial 4 will always be left in position to print one of the

numerals 5, and not in a position intermediate two numbers, the dial 4 is provided over a portion of its periphery with ten notches 6, which are engageable with a detent roller 7 rotatably mounted by a pin 8 on a lever 9 which is fulcrumed at 10 and is urged against the dial 4 by a helical spring 11 compressed between the upper end of lever 9 and a fixed support 12.

In prior constructions the indexing lever 1 was solidly secured to the dial 4 and sufficient force had to be exerted on the lever to rotate the dial against the full resistance offered by the detent roller 7. Furthermore, the resultant motion was relatively jerky because of the great changes in the resistance afforded by the detent roller as it rolled over the teeth 14 defined by the notches 6. In accordance with the present invention, we couple the lever 1 to the dial 4 for limited lost motion with respect thereto, and utilize the movement of the lever in taking up the lost motion to move the detent roller substantially clear of the notches 6.

Thus the lever 1 is formed integrally with a flat ring 15 which lies against the side of the dial 4 and is rotatable on a hub 16 secured to the dial 4. The ring 15 is held on the hub 16 by the heads 17 of a pair of pins 18 which extend from the dial at diametrically opposite points thereon.

There is slidably secured to the face of the dial 4 a cam 19, this cam being positioned immediately back of the ring 15 and having a large slot through which the hub 16 projects so that the cam is free to slide radially in the direction of the line III—III of Fig. 1. The cam is confined to sliding movement in the direction of the line III—III by the pins 18—18 and a pin 20 which all engage slots in the cam 19.

The cam 19 is provided with an outturned ear 21 which normally engages one side of the lever 1 and it is also provided, at a substantially diametrically opposite point, with an ear 22 that normally engages an arm 23 which projects from the ring 15 substantially diametrically opposite to the lever 1. In response to counterclockwise force applied to the lever 1, the ring 15 rocks freely on the hub 16 and the lever 1 bearing against the ear 21 moves the cam 19 bodily to the left from the position shown in Fig. 1 into the position shown in Fig. 2, this movement being permitted by the slots engaging the pins 18 and 20. Thereafter further movement of the lever 1 moves the dial 4 and the shaft 2. Likewise, if force is applied to the lever 1 in a clockwise direction, pressure of the arm 23 against the ear 22 shifts the cam 19 to the limit of its outward movement before the dial 4 is forced to rotate.

The cam 19 is provided with an arcuate edge 25 substantially concentric with the teeth 14 and when the cam is in its normal position as shown in Fig. 1, the edge 25 is sufficiently retracted to permit movement of the roller 7 fully into the notches 6. However, when the cam 19 is shifted to its outer position, as previously described, the arcuate edge 25 approaches the tips of the teeth 14, as clearly shown in Fig. 2, and carries the detent roller 7 almost clear of the teeth 14.

The net result of the improved mechanism described is that by introducing a little lost motion between the indexing lever 1 and its associated dial 4, the force required to rock the lever and the dial is greatly reduced. This reduction in the resistance to rotation afforded by the spring detent mechanism probably results largely because of the fact that the edge 25 of the cam 19

exerts force against the detent roller that is more directly in alignment with the direction of movement of the roller. In actual tests, a mechanism constructed as shown in the drawing has reduced the force necessary to rotate the dial from approximately 4½ lbs. to 2½ lbs., a reduction of nearly one-half in the total force required.

This reduction in the force required is obtained without sacrificing positive retention, since the full force of the spring 11 is effective to engage the roller 7 in one of the notches 6 when the indexing lever 1 is released.

Although the operation is much easier because of the use of the cam 19, the operator is still able to "feel" the movement of the teeth 14 past the detent roller 7 because, as already pointed out with reference to Fig. 2, the edge 25 does not carry the detent completely clear of the teeth.

In the construction described with reference to Figs. 1, 2, 3 and 4, the notches 6 are approximately triangular in shape and if sufficient torque were applied to the dial 4 it could always be rotated without employing the cam 19. However, a modified construction may be employed, as shown in Fig. 5, in which the dial 4' is positively locked against rotary movement except when the detent roller 7' is partially disengaged from the disc, as described in connection with Fig. 1.

It will be readily observable that the only difference between the construction shown in Fig. 1 and that shown in Fig. 5 is that the notches 6' in Fig. 5 are somewhat deeper and have straight parallel side portions 6a which engage the rollers 7' when the latter are in locking position. By virtue of the fact that the rollers 7' engage against flat surfaces extending approximately radially from the center of the disc 4', a torque applied to the disc develops no radial component capable of forcing the rollers 7' out of engagement with the notches. Hence the dial 4' cannot be rotated until the detent rollers 7' have first been partially disengaged from the notches 6' by the action of the cam 19. To simplify the drawing, the cam 19 has not been shown in Fig. 5, but its construction and operation will be exactly the same as that shown in Fig. 1.

Although for the purpose of explaining the invention specific embodiments thereof have been described in substantial detail, it is to be understood that various changes may be made in the particular constructions shown without departing from the invention, which is to be limited only to the extent set forth in the appended claims.

We claim:

1. In an indexing device for a postage printing machine or the like, in combination, a rotatable member, an arcuate notched plate element, and a cooperating spring detent element radially movable to follow the notches in said plate element in response to relative rotation between said elements, one of said elements being mounted on said rotatable member, an actuating member rotatable coaxially with said rotatable member, means coupling said actuating member to said rotatable member with lost motion therebetween, and means responsive to movement of said actuating member relative to said rotatable member through said lost motion for radially moving one of said elements to partially disengage said detent from said notched plate.

2. In an indexing device for a postage printing machine or the like, in combination, a rotatable plate member, an actuating member rotatable coaxially with said rotatable plate member, an element mounted on said rotatable plate member for limited radial movement with respect thereto, said actuating member engaging said element and shifting it radially in response to initial rotation of said actuating member relative to said rotatable plate member, and means thereafter coupling said element positively to said rotatable plate member for driving the latter as said actuating member is rotated, brake means comprising a radially movable element for controlling rotation of said rotatable plate member, the aforesaid shifting of said radially movable element being adapted to partially disengage said brake means.

3. In an indexing device for a postage printing machine or the like, in combination, a rotatable member, a coaxial rotatable actuating member, an arcuate notched detent plate on said rotatable member, a radially movable, spring-actuated detent engaging said notched plate, a smooth, arcuate member mounted for radial movement on said rotatable member between a first position in which it is retracted clear of said detent and a second position in which it engages the detent and at least partially disengages said detent from said notched member, and means responsive to initial movement of said actuating member for shifting said smooth, arcuate member from said first to said second position, said means thereafter coupling said actuating member to said rotatable member for driving the latter.

4. In an indexing device for a postage printing machine or the like, in combination, a rotatable member having an arcuate notched edge portion, a spring detent radially movable with respect to said rotatable member for engaging the notched edge portion of said rotatable member, a cam element mounted on said rotatable member, an actuating member rotatable coaxially with said rotatable member, and lost motion means coupling said actuating member and said cam element to said rotatable member, said

actuating member moving said cam element during said lost motion period to partially disengage said detent from the notched edge portion of said rotatable member, whereby said detent engages only the outer ends of the teeth forming said notched edge portion as said actuating member moves said rotatable member.

5. In an indexing device for a postage printing machine or the like, in combination, an actuating member, a rotatable plate member adapted to be moved by said actuating member, rack means formed on the periphery of said plate member, a spring detent adapted to engage said rack means, the inner portions of the teeth of said rack having walls extending substantially radially with respect to the axis of said rotatable plate member, the outer portions of the walls of each tooth extending toward each other to form cam surfaces on the ends of each tooth, and means movable by the initial movement of said actuating member to disengage said detent from the inner portions of said teeth so that only the cam-shaped portions of the teeth engage the detent as said actuating member turns said plate member.

6. In an indexing device for a postage printing machine or the like, in combination, a rotatable member, an arcuate notched plate element, a cooperating spring detent element radially movable to follow the notches in said plate element in response to relative rotation between said elements, one of said elements being mounted on said rotatable member, an actuating member, means mounting said actuating member for rotation with said rotatable member and also for shifting movement transversely of the axis of rotation of said rotatable member, means coupling said actuating member to said rotatable member with lost motion therebetween, and means responsive to movement of said actuating member relative to said rotatable member through said lost motion for radially moving one of said elements to partially disengage said detent element from said notched plate element.
